CLAIM

The ornamental design for a light bulb, as shown and described.

DESCRIPTION

FIG. 1 is a first perspective view of a light bulb showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is the using state of the light bulb; and,

FIG. 10 is an enlarged view of the selected portion 10 in FIG. 1.

In the drawings, the evenly-spaced broken lines depict environment that forms no part of the claim; the dash-dot-dash broken lines represent sectional designations that form no part thereof.

1 Claim, 10 Drawing Sheets
